UNITED STATES PATENT OFFICE.

FREDERIC BARR, OF NEW YORK, N. Y.

BUCKLE.

SPECIFICATION forming part of Letters Patent No. 718,240, dated January 13, 1903.

Application filed June 10, 1902. Serial No. 111,077. (No model.)

to all whom it may concern:

Be it known that I, FREDERIC BARR, a citizen of the United States, and a resident of the city of New York, borough of Manhattan, in the county and State of New York, have invented a new and Improved Buckle, of which the following is a full, clear, and exact description.

This invention relates to what are known as "lever-buckles" for holding belts or straps made of any flexible material used for belts or straps in which the belt or strap is secured without injury to the belt or strap, and it can be quickly and easily operated. In these buckles there is usually combined with the buckle-frame a hinged lever or clamp to hold by friction the free end of the belt or strap between the end of the lever and the buckle-frame.

My invention relates to what is known as a "double-end" buckle, doing away with fastening the belt or strap to the buckle permanently, the winged levers or clamps, which are made of metal, having double rabbeted edges for its clamping portion and a spring set in end of the winged levers held in place by the pivot-pin that holds the winged levers. The belt or strap is easily adjusted by drawing the free end of the belt or strap through the buckle. The spring in the end of the winged levers sets them at once and prevents it from being released until the winged lever is raised.

Figure 1 represents a view in perspective of a buckle made in accordance with my invention, showing it with belt attached; Fig. 2, a perspective view of said buckle closed and showing by dotted lines the pivot-pin which holds the winged levers and spring in place. Fig. 3 is a rear view of Fig. 2. Fig. 4 is a longitudinal central section of Fig. 2, showing winged levers closed and open and spring in position.

The frame of the buckle consists of upper and lower members 11, which incline upward from a central point, and parallel side members 12, and at the inner edge of each side member 12, at the front faces of said member, a longitudinal rabbet 13 is produced.

In the further construction of the buckle-frame a central transversely-located guide-loop 14 is formed offset from the front face of

the frame, which loop is provided at or near its upper end with a transverse opening 15, so that the ends of the thin belt material may be quickly and conveniently passed in a cross position beneath the guide-loop 14 at the front of the buckle, as is shown in Fig. 1, as the edges of the body material A may be simply slipped through the said slot or opening 15. 55 60

In the further construction of the buckle a pintle or pivot-pin 16 is passed through the top and bottom member of the frame back of the guide-loop 14, and the major construction of the frame is completed by addition of the locking-wings B, located in the space between the side members 12 of the buckle-frame, and the pivot-pin 16 being held to turn upon the latter through knuckles 17, arranged to interlock and through which the pivot-pin passes, 70 as is shown in Fig. 2. In the rear surface of the outer end of each locking-wing B a rabbet 18 is produced, and in the closed position of the wings the rabbeted surfaces of the wings fit snugly to the rabbeted surfaces of the buckle-frame and in such manner that the opposing edges of said part are flush at the back of the buckle and constitute gripping edges for the body material A of the belt, which is passed between said edges from the 80 back forwardly to be crossed beneath the guide-loop 14, as is shown in Fig. 1. The locking-wings B are held in their closed position by a spring 19, coiled around the pivot-pin 16 and having its end secured to the locking-wings with the tension rearwardly applied. Under such a construction of buckle any strip of velvet or the thinnest ribbon fabric may be quickly and conveniently laced through the buckle and be held firmly and 90 against displacement around the waist of the wearer. 85

What I claim as new, and desire to secure by Letters Patent, is—

As an improved article of manufacture a buckle consisting of a frame, having its top and bottom members inclined upwardly and outwardly in opposite directions from a central point and having the inner edges of its side members rabbeted at the front and a central transverse offset guide-loop connecting the top and bottom members and provided with a transverse slot, a pivot-pin in frame at the rear of the guide-loop and spring-con-

trolled wings mounted upon the pivot-pin and having their outer end rabbeted at the back to fit in the rabbeted portion of the frame and the outer ends of the wings being flush 5 at the back of the frame, when the wings are closed.

In testimony whereof I, FREDERIC BARR,

have signed my name to this specification, in the presence of two subscribing witnesses, this 13th day of May, 1902.

FREDERIC BARR.
